UNITED STATES PATENT OFFICE.

EDNA ECKERT, OF NEWARK, NEW JERSEY.

DESIGN FOR A SHRINE.

Application filed January 31, 1929. Serial No. 29,856. Term of patent 14 years.

To all whom it may concern:

Be it known that I, EDNA ECKERT, a citizen of the United States, residing at 300 Verona Avenue, Newark, in the county of Essex and State of New Jersey, have invented a new, original, and ornamental Design for Shrines, of which the following is a specification, reference being had to the accompanying drawing, forming part thereof.

In the accompanying drawing showing my new design:

Fig. 1 is a front elevation of a shrine in accordance with my design.

Fig. 2 is a central vertical section of the shrine illustrated in Fig. 1.

The shrine in accordance with my invention comprises a base 10, a back wall 11, side walls 11^a and 11^b, and eaved roof 12. The wall 11 is provided with window openings 13, with which are associated stained glass panels 14, which are ornamented as shown. An image or statue 15 is mounted on the base 10 forwardly of the wall 11 and glass panels 14.

I claim:

The ornamental design for a shrine, substantially as shown and described.

EDNA ECKERT.
